UNITED STATES PATENT OFFICE.

JAMES F. GYLES, OF CHICAGO, ILLINOIS.

AUTOMATIC CAR-STOVE-FIRE EXTINGUISHER.

SPECIFICATION forming part of Letters Patent No. 278,236, dated May 22, 1883.

Application filed March 3, 1883. (No model.)

To all whom it may concern:

Be it known that I, JAMES F. GYLES, of Chicago, in the county of Cook and State of Illinois, have invented a new and useful Improvement in Automatic Car-Stove-Fire Extinguishers, which improvement is fully set forth in the following specification, reference being had to the accompanying drawings, in which—

- 10 Figure 1 is a perspective view of the entire apparatus in position for use; Fig. 2, a perspective view of a portable apparatus in condition for use; Fig. 3, the detached key. Fig. 4 is a side elevation of the supporting-frame, showing the operating mechanism on the outside thereof. Fig. 5 is an elevation, partly in section, of the fluid-cylinder, showing the sheathed air-chamber; Fig. 6, a detached vertical section of the air-chamber and sheath.
- 15 Fig. 7 is an elevation of the internal shaft. Fig. 8 is a detached elevation of the sheath, showing the disk or flange. Fig. 9 is an elevation of gear-shaft.
- 20 Fig. 10 is a perspective view of the entire apparatus in position for use; Fig. 11, a perspective view of a portable apparatus in condition for use; Fig. 12, the detached key. Fig. 13 is a side elevation of the supporting-frame, showing the operating mechanism on the outside thereof. Fig. 14 is an elevation, partly in section, of the fluid-cylinder, showing the sheathed air-chamber; Fig. 15, a detached vertical section of the air-chamber and sheath.

This improvement relates to that class of inventions described in my application filed February 7, 1883, and is for the purpose of providing an air-tight fluid-reservoir, in combination with a suitably-sheathed air-chamber, as a car-stove-fire extinguisher, which may likewise be rendered available for the purpose of extinguishing fire in a building, as hereinafter more fully stated.

The cylinder, with convexo-concave extremities, is made of copper eight and three-fourths inches in diameter, (or may be made of any other suitable metallic substance and of greater or smaller dimension,) in two or three sections, the lower section for holding the required quantity of a suitable liquid fire-extinguishing compound, and when the sections are united (by means of the couplings described in my previous application) measures about forty-six inches in length, and will sustain the pressure required for accomplishing the purpose, in manner hereinafter more particularly described.

The fluid-cylinder is vertically adjusted upon a metallic stand, E'', and secured to the inside of the supporting-frame B, and is connected to the fire-box of the stove by suitable

tubes, D' D'' D''', a cast-iron tube having been first placed into the aperture (previously made) at the back of the stove to receive the extremity of tube D'''.

In order to prevent the possible displacement of the fluid-reservoir by an overturning of the car, an annular rim, X, having lugs (with apertures) X' X'', is placed over its concave top, and by means of the rods X'' X''' and swivels X''' X''' bolted to the floor, as more particularly 55 stated in my application filed February 7. Thereby it becomes immovably fixed in a position for use, as at Fig. 1.

The air-chamber C consists of a cylinder, which may be made in sections, and subsequently united by brazing or in any other convenient manner, of copper or cast-steel, or of any other suitable metal, with convexo-concave extremities, about twenty-six inches long by eight and nine-sixteenths of an inch diameter, 60 or of any greater or smaller dimension or shape to suit the requirement, provided with a metallic sheath, C', having a suitable flange, C'', around the lower part of same, being open at one end and convex at the other, is made to 65 slide closely around upon the chamber from its lower extremity upward a suitable distance, in order that the compressed air, when released from the air-chamber, as hereinafter more fully stated, shall not come in contact with the liquid, but that its force, acting directly upon the sheath and its auxiliary flange, shall expel the same. The flange C'' is made of rubber and is permanently attached to the sheath, or may be made of cork or wood, or of metal faced with 70 rubber, and as a modification it may be made of suitable diameter and placed upon the surface of the liquid under the sheath, or to take the place of it altogether; but in such cases the fluid-cylinder should be first tested in order to be satisfied that it is in all respects 75 absolutely air-tight.

Upon the removal of the convex top of the fluid-reservoir the sheathed air-chamber and flange is placed within it immediately above 80 the liquid, and is supported temporarily by springs a a, as at Fig. 5. Apertures are provided at each extremity of the chamber, as also a concavity upon each side of it, at a suitable distance from the top, as shown at V'' V'', 85 90 95 100

Fig. 6, having an orifice directly in the center of each, with bushing around same, as at *i i*, through which the horizontal shafts *V' V'*, working also in journals *U U*, attached to the 5 inside of the chamber, are extended about an inch, and suitable four-sided attachments secured thereupon, as at *S'' S''*, to work close up to the bushing. Upon the other extremities of the shafts eyelets are provided, as at *e e*, 10 which are attached to the eyelets *e' e'*, provided upon the upper ends of the two vertical rods *v' v'*, and from thence the lower ends of same are connected by eyelets *E' E'* to the double eyelet terminal *E*, which is provided upon the 15 lower valve-stem. The rods, however, are made in two parts and are connected also by eyelets, as at *e'' e'''*. The eyelets *e'''* are elongated, and the eyelets *e''* are bent over, in order that when either shaft is employed by the 20 mechanism hereinafter described to lift the valve from its socket the bent-over eyelet upon the rod connected to the inoperative shaft shall readily slide upward on the elongated eyelet, as most clearly shown at Fig. 5. The 25 upper valve, *W*, is ordinarily held loose in the socketed bushing *w* (which is soldered to the chamber) by the stem-guide *b''*, so that it may automatically open and close the aperture by the pressure employed in charging the receptacle. The bushing *w'*, attached around the exterior of the aperture, is threaded in order 30 that a suitable air-pump may be secured to the same, as also to receive a cap, *w''*, which is correspondingly threaded, in which is provided 35 a suitable orifice to admit the extension of the valve-stem *W'*, which, when the air-chamber is charged, protrudes through the same, and, the end of it being threaded, a tap, *w'''*, which is also threaded, is thereupon attached to hold 40 the valve tightly in its place.

In charging the receptacle the tap and cap are of course removed, and any suitable air-pump may be attached to the bushing and employed to compress the air thereinto until the 45 required force is obtained, which may be equal to about one hundred and fifty or two hundred pounds to the square inch, as will be indicated by attaching a suitable pressure-gage upon the top of the globe-valve *W'''*, which has been 50 previously opened, as at *W'''*, Fig. 5. After charging the chamber the pump is detached and the cap and tap are replaced, and, the globe-valve having been closed, the pressure-gage may also be detached. The recessed ends of 55 the shafts *S S* (shown at Fig. 9) are attached to the four-sided terminals of the shafts *V' V'* (shown at *S''*, Fig. 7) through suitable apertures in the reservoir by means of the collars *o' o'* and couplings *o'' o''*, which are screwed up 60 on the threaded bushings *o o*, provided around the apertures before stated. Upon the other extremities of the shafts *S S* the beveled cogs *s' s'* are attached, as at Figs. 1 and 5, which work into the correspondingly-beveled cogs *s s*, 65 attached upon short horizontal projections which work in journals provided upon the sides

of the supporting-frame and are connected to the toothed gearing *r*. (Shown at Fig. 4.) The operating mechanism there shown consists of the toothed gearing *r*, directly under which 70 is a bar, *R*, attached near its center to the side of the supporting-frame, having similar toothed gearing at both extremities *r' r'*. Attached also to the supporting-frame, directly under the bar *R*, is a pendulum-bar, *L*, which has a 75 corresponding toothed gearing, *r''*, upon its upper end, with elongated fulcrums attached thereunder to the frame also, as at *w*, Fig. 4, and a flattened weight, *P*, at its lower extremity, the latter having rollers attached upon 80 the sides. At the bottom of the frame are attached parallel curved planes *V V*, with a suitable guideway between them and a depression at the center of the arc.

To prevent the premature discharge of the 85 liquid, and the consequent extinguishment of the fire, the pendulums ordinarily hang out of gear (or engagement) with the toothed extremity of the bar *R*, and are so held by the governor-bar *G* until the apparatus is inclined to 90 an angle of forty-five degrees. When, therefore, the deflected car attains such an angle in any direction, one of the pendulums must inevitably be released and thrown into gear, which, then acting (through the mechanism 95 shown at Fig. 4) upon the beveled cogs *s* and *s'*, operate shafts *S* and *V'*, thereby lifting the escape-valve *V* from its socket, as shown at Fig. 6, when the compressed air instantly strikes the sheath with great force, causing 100 the springs *a a* to yield, sending it and the flange down upon the liquid, which is in consequence driven through the tubes into the fire-box of the stove.

The convex extremity of the sheath 105 descends into the concave bottom of the reservoir, thereby forcing out the whole contents. Thus it will be understood that when, by an overturning of the car, the reservoir becomes 110 upset or is entirely turned upside down, the 115 continuous discharge of the liquid cannot be obstructed.

In a fire-extinguisher for a building, the reservoir is secured vertically upon a wheeled truck by annular rim *X*, lugs *X' X'*, rods *X'' X''*, 115 and swivels *X''' X'''*, which are bolted to the flooring of same, as shown at Fig. 2, and is provided with a vertical tube coupled to its 120 concave bottom, upon the upper part of which hose is attached. The truck being provided with axles and wheels, (and a suitable handle,) the whole can be readily moved about the 125 building and a fire extinguished by attaching the key and turning the shaft, in order to lift the escape-valve, and then directing the discharge of the fluid through the hose-pipe.

Having thus described my invention, what I claim as new, and desire to secure by Letters Patent, is—

1. In a fire-extinguishing apparatus, a fluid-containing reservoir, combined with a compressed-air cylinder having suitably-controlled 130

- inlet and outlet ports, and provided with a sheath which is adapted to be projected by the compressed air into the extinguishing-fluid, substantially as set forth.
5. A fluid-containing reservoir, combined with a compressed-air cylinder having suitably-controlled inlet and outlet ports, and a sheath which is provided with an auxiliary flange or piston, substantially as and for the purpose set forth.
10. A fluid-containing reservoir, combined with a compressed-air cylinder having suitably valved supply and exhaust ports, the shafts V' , the sheath C' , and means whereby upon the revolution of the said shaft the outlet-port of the compressed-air cylinder is opened, as and for the purpose set forth.
15. The reservoir A , cylinder C , and sheath C' , combined with the tubing $D'D''D'''$, shafts V' , and means whereby the revolution of said shafts will open the eduction-port of the compressed-air cylinder, as and for the purpose set forth.
20. The reservoir A , mounted upon the truck T , compressed-air cylinder C , and sheath C' , combined with means for releasing the eduction-valve within the compressed-air cylinder, and suitable tubing for directing the discharge of the extinguishing-fluid, substantially as set forth.
25. The reservoir A , cylinder C , and sheath C' , combined with the valve V , eyelets $E E'$, rods v' , connecting-eyelets $e e' e'' e'''$, shafts V' , journals U , and external means for operating the shafts V' , substantially as set forth.
30. The gearing-shafts S , having square recesses S' , collars o' , and couplings o'' , combined with shafts V' , square attachment S'' , and bushing o , substantially as set forth.
35. The gearing-shafts S , having square recesses S' , collars o' , and couplings o'' , combined with shafts V' , square attachment S'' , and bushing o , substantially as set forth.
